Israel*Attorney, Agent, or Firm*—Pollock, Vande Sande & Priddy[21] Appl. No.: **322,487****ABSTRACT**[22] Filed: **Oct. 14, 1994**

A new and distinct rose plant of the Hybrid Tea class named 'Seemore'. The plant is characterized by vigorous growth, non-fragrant flowers with purple red petals (R.H.S. 57 A-58 B on the inner side and R.H.S. 55D on the outer side), early and prolific flower production, and fast and good propagating features.

U.S. PATENT DOCUMENTS

P.P. 4,391 3/1979 Delbard Plt./20

3 Drawing Sheets**1****CROSS REFERENCE TO RELATED PATENTS**

The new and distinct cultivar described and illustrated herein is related to the cultivar 'Odem', which is the subject of U.S. Plant Pat. No. 8,620, issued Mar. 1, 1994.

2

same conditions and under the same roof. The following observations were made between the present invention and a plant of the parent cultivar, 'Odem'.

FIELD OF THE INVENTION

The present invention is concerned with a new variety of a Hybrid Tea rose discovered by me and being a mutation of 'Odem', which is the subject of U.S. Plant Pat. No. 8,620 which is a mutation of 'Carola', which is the subject of U.S. Plant Pat. No. 8,290, issued Jul. 6, 1993, which in turn is a mutation of 'Deladel' ('Mme. G. Delbard'), which is the subject of U.S. Plant Pat. No. 4,391, issued Jul. 6, 1993.

BACKGROUND OF THE INVENTION

This mutation was discovered as a branch on an 'Odem' plant in 1993 on a cultivated area in a farm, located in Moshav Hayogev, located in Izra'el Valley, Israel, with an average night temperature of 25° C. in summer and 0°-5° C. in winter.

The branch was vegetatively propagated from cuttings by self-rooting. From these cuttings plants were grown in a green house where they were further vegetatively propagated from cuttings by self-rooting.

The resulting plants were found to be stable in their botanical characteristics, as are described below and as illustrated by typical plants parts in the attached photographs.

Asexual propagation of this new variety was performed at Moshav Ha-yogev, Israel.

The presently claimed cultivar was a natural mutation of the cultivar 'Odem'.

All color definitions in this application are taken from The Royal Horticultural Society of London, England, (R.H.S.) Colour Chart.

The data in the following table of comparison is based on observations made in the greenhouse at Moshav Ha-yogev, Israel, where plants were grown side-by-side, under the

SUMMARY OF THE INVENTION

The present invention provides a Hybrid Tea rose variety which includes the following characteristics which distinguish the new variety from the cultivar 'Odem', to which it is related, and for which the following differences have been noted:

Young shoot: Hue of anthocyanin coloration.
 Prickles: Shape upper.
 Petiole: Rachis.
 Foliage: Color.
 Flower stem: Length.
 Flower: Number of petals, life on the plant.
 Petal: Color.
 Stamen: Predominant color of filament.
 Stigma: Position as compared with anthers, color.
 Pollen: Color.
 Filament: Color.

BRIEF DESCRIPTION OF THE DRAWINGS

Sheet 1 represents a typical specimen of the present invention, illustrating a flower bud at picking stage, a part of the stem, leaflets, and flowers at various opening stages;

Sheet 2 represents a side-by-side comparison of the flower size, bud size and color of petal between a typical specimen of the present invention, 'Seemore' (on the left) and the parent variety, 'Odem' (on the right); and

Sheet 3 represents another side-by-side comparison of various flower parts between a typical specimen of the present invention, 'Seemore' (on the left) and the parent variety, 'Odem' (on the right).

The colors in the drawings are as true as is reasonably possible in an illustration, depicting green and red colors. The plants illustrated in Sheets 2 and 3 were grown under exactly the same conditions, in a greenhouse, at Moshav Ha'yogev, each on its own roots, and being visibly healthy.

BOTANICAL DESCRIPTION

The following observations were made in Moshav Ha'yogev, Israel in 1993 in a greenhouse:

Plant:

Form.—Bush.
Growth habit.—Semi-upright.
Height (cm).—150–200.
Spread (cm).—Ca. 80.

Wood:

Color.—Mature: Light brown.
Bark.—Color: young: green. mature: light brown.

Stem:

Color.—Young: R.H.S. 146 B yellow green. Mature: R.H.S. 143 A green.

Young shoot:

Anthocyanin coloration.—Medium to strong.
Hue of anthocyanin coloration.—Red-brown.

Prickle(s): present.

Size.—Length (mm): ca. 5. Height (mm): ca. 6.

Shape.—Upper side: concave to straight. Lower side: concave.

Color.—Young: R.H.S. 176 A grey orange. Mature: R.H.S. 173 A grey orange.

Short prickles:

Quantity.—Few.

Long prickles:

Quantity per 10 cm at center of stem.—Few (8).

Leaf:

Size.—Length (mm): 120–150. Width (mm): 75–115.

Green color.—Medium.

Glossiness of upper side.—Weak.

Number of leaflets in the compound leaf.—3, 5, or 7.

Leaflet:

Cross section.—Straight.

20 *Undulation of margin.*—Weak to medium.

Margin.—Serrated.

Terminal leaflet:

Length of blade (mm).—50–65.

Maximum width (mm).—30–43.

25 *Shape of base.*—Rounded.

Petiole:

Length (mm).—15–20.

Rachis.—Straight, flat, hairy.

Color.—R.H.S. 143 A/144 A green.

30 *Foliage:*

Young.—Color: upper side: center: R.H.S. 152 A yellow green. rims: R.H.S. 166 AB grey orange. lower side: R.H.S. 176 AB grey orange.

Mature.—Color upper side: R.H.S. 137 A green. lower side: R.H.S. 137 C/138 A green.

Stipule:

Stitched, split tip.

Bloom:

Borne.—Multiply/in a cluster.

Flowering shoot:

40 *Number of flowers.*—Few (3–5).

Flowering habit:

Continuous.

Flowering stem:

Length (cm).—40–70.

Color.—Light green.

45 *Flowering pedicel:*

Number of hairs or prickles.—Very few to few.

Flower bud:

Longitudinal section.—Ovoid.

Size.—Medium (30–50 mm).

50 *Flower:*

Type.—Double.

Diameter (mm).—Ca. 80.

Fragrance.—None.

View from above.—Rounded.

55 *Side view.*—Upper side: flattened-convex. Lower side: flat.

Number of petals.—43–58.

Life.—On the plant 17–21 days. In a vase: 12–15 days.

Fading with age.—Begins after 7–10 days.

60 *Sepal:*

Length (mm).—30–43.

Extensions.—Medium.

Color.—Upper side: R.H.S. 143 B/144 C green-yellow green. Lower side: R.H.S. 144 A yellow green.

65 *Petal:*

Size.—Length (mm): 37–45. Width (mm): 39–49.

Shape.—Rounded.
